United States Patent Office

Des. 177,756
Patented May 22, 1956

177,756

CHRISTMAS TREE STAND

Matt E. Peterson and Donive R. Randall, Whitefish, Mont.

Application July 10, 1953, Serial No. 25,880

Term of patent 14 years

(Cl. D35—3)

Fig. 2.

Fig. 1.

Fig. 3.

Fig. 4.

Fig. 5.

Fig. 1 is a front elevational view of a Christmas tree stand, showing our new design;

Fig. 2 is a top plan view of the stand of Fig. 1;

Fig. 3 is a bottom plan view of the stand;

Fig. 4 is a rear elevational view of the stand;

Fig. 5 is a side elevational view of the stand, looking at the left hand end of Fig. 1.

We claim:

The ornamental design for a Christmas tree stand, as shown.
